MUD PUMP

**Albert A. Ashton, Houston, Tex., assignor to Em-
-sco Derrick & Equipment Company, Los An-
-geles, Calif., a corporation of California**

Application October 26, 1942, Serial No. 463,316

7 Claims. (Cl. 103—177)

My invention relates to reciprocating pumps, and relates in particular to an improvement in double acting duplex pumps of the type employed in the oil drilling industry for the purpose of pumping drilling mud under high pressure.

It is an object of the invention to provide a pump of this character, which is rigid and amply strong for the service for which it is designed, but is extremely light in weight as compared to many pumps which have been used and are now in use, of no greater capacity.

It is an object of the invention to provide a pump having pistons arranged to be reciprocated through the use of piston rods which are connected to a power source, this pump comprising essentially a front section and a rear section of similar form, these sections being connected together by the application of welds located in a plane or in planes which cross the axes of the pump cylinders, these welds being disposed between the front and rear sections and joining the same in a rigid lightweight hollow pump structure.

A further object of the invention is to provide in a pump structure of this type front and rear sections adapted to be secured together by use of welds, in a spaced arrangement determined in accordance with the length of the cylinder liner to be employed therein which in turn is controlled by the length of stroke of the pump piston. For example, these front and rear sections may be connected rigidly together in a pump adapted to receive a liner of a length to accommodate a twelve-inch or fourteen-inch stroke, or these sections may be welded together in positions to receive a longer liner, for example, one which will accommodate an eighteen-inch stroke. In the invention the front and rear sections have pump chambers which provide mouths or openings to receive the end portions of the liners, there being open spaces between the front and rear sections across which the liners extend, and in which the liners are exposed. A number of additional advantages result from this arrangement. The amount of metal used in the pump is reduced, and the intermediate portions of the liner are exposed or have communication with the exterior of the pump, making it possible for the pump operator to readily observe any leakage which may occur along the exterior of the pump liner from the pump chambers disposed at the ends of the liner. Being thus observed, the leakage may be corrected by tightening up on the packing or replacing the same, thereby avoiding the cutting of metal parts as the result of a con-

tinued flow of mud under high pressure through the leakage paths.

5 A further object of the invention is to provide a simple pump section which may be employed in the manner described herein, this pump section having a U-shaped hollow member comprising a laterally extending hollow inlet body with hollow arms extending upward from the ends of the inlet body, and pump chambers located in 10 the space between the upwardly extending arms, in the manner and for the purpose brought out in detail hereinafter.

Referring to the drawing, which is for illustrative purposes only.

15 Fig. 1 is a side elevation showing a power pumping device having my simple pump as an operative part thereof.

Fig. 2 is a perspective view showing the front and rear pump sections spaced apart in axial direction, to show the cooperative relation of the front and rear sections.

Fig. 3 is an enlarged sectional view of Fig. 1, taken as indicated by the line 3—3 therein, a portion of the view being broken away to show the 25 interior form of the valve pots employed in duplicate in a pump section.

Fig. 4 is a section taken as indicated by the line 4-4 of Fig. 3, to show the manner in which the cylinder liners are disposed and held in the mouths.

In Fig. 1 I show a power pumping device comprising a power unit 10 and a pump 11 of duplex double acting type. This pump 11 has therein a pair of cylinders or liners 12 in side by side relation. As shown in Fig. 4, each of these liners 12 receives a piston 13 which is reciprocated through a piston rod 14, these piston rods 14 extending through packing means 15 carried by the end wall 16 of the pump 11 disposed contiguous to the power unit 10, as shown in Fig. 1. It will be understood that this power unit 10 has therein the customary power driven means for reciprocating the piston rods 14, which need not be shown, since the present invention relates to the fluid end of the device shown in Fig. 1, namely, the pump 11.

The pump 11 has a front section 17 and a rear section 18, these sections being in many respects symmetrical, and involving differences as will be hereinafter pointed out. These sections 17 and 18 are shown in perspective in Fig. 2, in axial relation so that their points of similarity and differences may be observed. Each of these sections, as clearly brought out in Figs. 2 and 3, has a hollow U-shaped member 19 comprising a bot-

tom laterally extending hollow section 20, referred to as the hollow inlet member 20, and upwardly extending hollow legs 21 disposed at and connected to the ends of the hollow inlet member 20, these side portions 21 comprising valve pots for the pump sections, the lower ends of which valve pots communicate with the inlet member 20, and the upper ends of these valve pots 21 having openings 22 of such size that intakes and discharge valves may be passed therethrough into the valve pots 21, covers 23 being provided for the openings 22.

Each of the sections 17 and 18 includes a pair of juxtaposed pump chambers 24 of cylindric form. These pump chambers are disposed between the valve pots 21 and are positioned above the hollow inlet member 20. The walls of the chambers 24 merge with the walls of the valve pots 20, and each chamber 24 communicates through an opening 25 with an intermediate portion of the interior space of a valve pot 21. Above the pump chambers 24, each section 17-18 has a hollow outlet member 26, shown as a tubular wall, communicating with the upper portions of the valve pots 21. Each of the hollow inlet members 20 has a short cylindric wall 27 defining an opening 28, communicating with the interior of the hollow inlet member, as best shown in Fig. 4. These annular walls or connections 28 are disposed in a vertical or longitudinal plane extending between the pump chambers 24. In a similar manner, the hollow outlet members 26 are provided with outlet connections 29, preferably centrally thereof as shown in Fig. 2.

The sections 17 and 18 are connected together by use of known welding processes to form a rigid pump structure. The spacial relation of the sections 17 and 18 is determined in accordance with the length of stroke of the pistons to be employed in the pump of which the sections 17 and 18 are to become a part. In this procedure of joining the sections 17 and 18, tubular members 30 and 31 may be interposed respectively between the connections 27 and 29 of the hollow inlet members 20 and the hollow outlet members 26, and these tubular members 30 and 31 are joined with the connections 27 and 29 by use of annular bodies of welded metal 32 and 33, applied by use of the electric arc or oxy-acetylene flame. When these welds are formed, the sections 17 and 18 are rigidly connected together. The space between the pump chambers 24 of section 17 and the pump chambers 24 of the section 18 depends upon the spatial relation of the sections 17 and 18, which in turn is determined by the lengths of the inserted tubular members 30 and 31. Each of the pump chambers 24, as best shown in Fig. 4, has an annular liner receiving mouth 34, and the liners 12 are moved through openings 35 in the leftward ends of the pump chambers 24 of the section 17 into positions, as shown in Fig. 4, wherein the end portions of the liners will extend through the mouths 34 of the chambers 24, and the intermediate portions of the liners 12 will extend across the space between the adjacent ends of the pump chambers 24, as also shown in Fig. 1. Covers 36 are provided for the openings 35, and the liners 12 are held in position and forced rightwardly so as to compress packing rings 37 and 38, Fig. 4, by hollow frames 39 pressed rightward by screws 40 which pass through the covers 36.

Means are provided for connecting the hollow inlet members 20 with delivery piping through which the mud is carried to the pump. This

means comprises a flanged tubular inlet 41 projecting leftward from the hollow inlet member 20 of the front section 17, as shown in Figs. 2 and 4, so that the delivery piping 42 may be conveniently connected thereto as shown in Fig. 1. Also, outlet means are provided for connecting the hollow outlet members 26 with discharge piping, through which the pumped fluid is conveyed to the rotary hose of the well drilling system. This outlet means consists of a flanged outlet fitting 42, formed integrally with and communicating with the central portion of the tubular member 31. As shown in Fig. 1, an outlet T 43 is ordinarily connected to the outlet fitting 42, this T 43 having a surge chamber 44 connected to the upper portion thereof, and having one of its branches connected to the discharge piping 45, the other branch of the T being closed by a blind flange 46.

As hereinbefore explained, the capacity of a pump employing the sections 17 and 18, is determined in part by the spacing of the sections 17 and 18 to accommodate liners of a selected length. In the pump 11, shown in Figs. 1 and 4, the liners 12 are relatively long, and the pump, accordingly, has relatively high capacity due to the length of the piston stroke. For a shorter liner 12, the lengths of the tubular members 30 and 31 are decreased accordingly so that the sections 18 and 17 will be brought closer together, and for a liner of minimum length, the section 30 may be entirely eliminated and an extremely short section 31 may be employed, under which circumstances the tubular connections 27 of the sections 17 and 18 will be brought substantially into positions of abutment and will be welded directly together by the application of an annular body of welded metal.

Where the pump is to be operated against extremely high pressures, connecting bars 47 and 48 are provided, these bars 47 being formed in cooperative relation on the sections 17 and 18, above and below the chambers 24, and being connected together by means incorporating bodies of welded metal. Such means, where the sections 17 and 18 are spaced apart, include inserted bars 50 of proper length, the ends of which are joined to the bars 47 and 48 by welds 51. It will be understood that when the sections 17 and 18 are connected together in their closest relation, the ends of the bars 47 and 48 will be substantially in abutment and will be welded directly together. Feet 52 are shown on the lower part of the front section 17, on opposite sides of the central vertical plane of the pump 11, for connection to the skids 53 of the power pump assembly shown in Fig. 1.

As shown in Fig. 3, each valve pot 21 has there-in an annular inlet valve seat 55 through which communication of the inlet member 20 with the opening 25 of the associated pump chamber 24 is obtained, and each valve pot 21 has above the opening 25 an outlet valve seat 56. Inlet and outlet valves 57 and 58 are respectively secured in the valve seats 55 and 56.

I claim as my invention:

1. In a double acting duplex pump having pistons adapted to be reciprocated through piston rods connected to a power source, and a pair of removably secured liners to receive said pistons, the combination of: front and rear pump sections, each of said pump sections having a pair of juxtaposed pump chambers formed with liner receiving mouths in which opposite end portions of said liners are received, a transverse hollow inlet member below said pump chambers, a trans-

verse hollow outlet member above said pump chambers, means forming inlet valve seats connecting said inlet members with said pump chambers, and means forming outlet valve seats connecting said pump chambers with said outlet member; and means connecting said front and rear sections together in cooperative relation so as to form a rigid pump structure comprising annular bodies of welded metal connecting said hollow inlet members together and connecting said hollow outlet members together, said pump also embracing means to connect the interiors of said inlet members and said outlet members respectively to intake and discharge pipes.

2. In a double acting duplex pump having pistons adapted to be reciprocated through piston rods connected to a power source, and a pair of removably secured liners to receive said pistons, the combination of: front and rear pump sections, each of said pump sections having a pair of juxtaposed pump chambers formed with liner receiving mouths in which opposite end portions of said liners are received, a transverse hollow inlet member below said pump chambers, a transverse hollow outlet member above said pump chambers, means forming inlet valve seats connecting said inlet members with said pump chambers, and means forming outlet valve seats connecting said pump chambers with said outlet member; and means connecting said front and rear sections together in cooperative relation so as to form a rigid pump structure comprising tubular fluid conveying members and annular bodies of welded metal connecting said hollow inlet members together and connecting said hollow outlet members together, said tubular members being arranged between said sections above and below said pump chambers, and the length of said tubular members determining the spacial relation of said sections, and said pump also embracing means to connect the interiors of said inlet members and said outlet members respectively to intake and discharge pipes.

3. In a double acting duplex pump having pistons adapted to be reciprocated through piston rods connected to a power source, and a pair of removably secured liners to receive said pistons, the combination of: front and rear pump sections, each of said pump sections having a pair of juxtaposed pump chambers formed with liner receiving mouths in which opposite end portions of said liners are received, a transverse hollow inlet member below said pump chambers, a transverse hollow outlet member above said pump chambers, means forming inlet valve seats connecting said inlet members with said pump chambers, and means forming outlet valve seats connecting said pump chambers with said outlet member; and means connecting said front and rear sections together in cooperative relation so as to form a rigid pump structure comprising annular bodies of welded metal connecting said hollow inlet members together and connecting said hollow outlet members together, said pump also embracing means to connect the interior of said outlet members to a discharge pipe and means to connect the hollow inlet member of said front section to an intake pipe.

4. In a double acting duplex pump having pistons adapted to be reciprocated through piston rods connected to a power source, and a pair of removably secured liners to receive said pistons, the combination of: front and rear pump sections, each of said pump sections having a pair of juxtaposed pump chambers formed with liner re-

ceiving mouths in which opposite end portions of said liners are received, a transverse hollow inlet member below said pump chambers, a transverse hollow outlet member above said pump chambers, means forming inlet valve seats connecting said inlet members with said pump chambers, and means forming outlet valve seats connecting said pump chambers with said outlet member; and means connecting said front and rear sections together in cooperative relation so as to form a rigid pump structure comprising tubular fluid conveying members and annular bodies of welded metal connecting said hollow inlet members together and connecting said hollow outlet members together, said tubular members being arranged between said sections above and below said pump chambers, the length of said tubular members determining the spacial relation of said sections, said pump also embracing means to connect the interior of said outlet members to a discharge pipe and means to connect the hollow inlet member of said front section to an intake pipe.

5. In a double acting duplex pump having pistons adapted to be reciprocated through piston rods connected to a power source, and a pair of removably secured liners to receive said pistons, the combination of: front and rear pump sections, each of said pump sections having a pair of juxtaposed pump chambers formed with liner receiving mouths in which opposite end portions of said liners are received, a hollow U-shaped body comprising a transverse hollow inlet member positioned below said pump chambers and a pair of valve pots extending upward from the ends of said hollow inlet members along the sides of the respective pump chambers, the intermediate portions of said valve pots communicating with said pump chambers, and each of said valve pots having therein an inlet valve seat below and an outlet valve seat above the point of communication of the valve pot with a pump chamber, and a hollow outlet member communicating with the interiors of said valve pots above said outlet valve seats; and means connecting said front and rear sections together in cooperative relation so as to form a rigid pump structure comprising annular bodies of welded metal connecting said hollow inlet members together and connecting said hollow outlet members together, said pump also embracing means to connect the interiors of said inlet members and said outlet members respectively to intake and discharge pipes.

6. In a double acting duplex pump having pistons adapted to be reciprocated through piston rods connected to a power source, and a pair of removably secured liners to receive said pistons, the combination of: front and rear pump sections, each of said pump sections having a pair of juxtaposed pump chambers formed with liner receiving mouths in which opposite end portions of said liners are received, a hollow U-shaped body comprising a transverse hollow inlet member positioned below said pump chambers and a pair of valve pots extending upward from the ends of said hollow inlet members along the sides of the respective pump chambers, the intermediate portions of said valve pots communicating with said pump chambers, and each of said valve pots having therein an inlet valve seat below and an outlet valve seat above the point of communication of the valve pot with a pump chamber, and a hollow outlet member communicating with the interiors of said valve pots above said outlet valve seats; and means connecting said front and rear sections together in cooperative relation so as to

form a rigid pump structure comprising tubular fluid conveying members and annular bodies of welded metal connecting said hollow inlet members together and connecting said hollow outlet members together, said tubular members being arranged between said sections above and below said pump chambers, the length of said tubular members determining the spacial relation of said sections, said pump also embracing means to connect the interior of said outlet members to a discharge pipe and means to connect the hollow inlet member of said front section to an intake pipe.

7. In a double acting duplex pump having pistons adapted to be reciprocated through piston rods connected to a power source, and a pair of removably secured liners to receive said pistons, the combination of: front and rear pump sections, each of said pump sections having a pair of juxtaposed pump chambers formed with liner receiving mouths in which opposite end portions of said liners are received; a hollow U-shaped body comprising a transverse hollow inlet member positioned below said pump chambers and a pair of valve pots extending upward from the ends of

5 said hollow inlet members along the sides of the respective pump chambers, the intermediate portions of said valve pots communicating with said pump chambers, and each of said valve pots having therein an inlet valve seat below and an outlet valve seat above the point of communication of the valve pot with a pump chamber, and a hollow outlet member communicating with the interiors of said valve pots above said outlet valve seats; means connecting said front and rear sections together in cooperative relation so as to form 10 a rigid pump structure comprising annular bodies of welded metal connecting said hollow inlet members together and connecting said hollow outlet members together, said pump also embracing means to connect the interiors of said inlet members and said outlet members respectively to intake and discharge pipes; and reinforcing bars 15 extending between said front and rear sections on opposite sides of a vertical plane extending lengthwise of the pump, said bars being connected by welds.

ALBERT A. ASHTON.
